UNITED STATES PATENT OFFICE

161,634

POPCORN DISPLAY DEVICE

Thomas H. Komstohk, Sr., Indianapolis, Ind.

Application October 5, 1949, Serial No. 5,315

Term of patent 14 years

(Cl. D52—3)

To all whom it may concern:

Be it known that I, Thomas H. Komstohk, Sr., a citizen of the United States, residing at Indianapolis, Marion County, Indiana, have invented a new, original, and ornamental Design for a Popcorn Display Device, of which the following is a specification, reference being had to the accompanying drawing, forming part thereof.

Fig. 1 is a front elevation of a popcorn display device embodying my new design; Figs. 2 and 3 are elevational views of opposite sides of the device; Fig. 4 is a rear elevation; and Fig. 5 is a top plan view.

I claim:

The ornamental design for a popcorn display device, as shown.

THOMAS H. KOMSTOHK, SR.
